UNITED STATES PATENT OFFICE

2,154,321

STEERING MECHANISM FOR WATER AND AIRCRAFT

Henry C. Briggs, Brooklyn, N. Y.

Original application October 10, 1936, Serial No. 105,112. Divided and this application June 11, 1937, Serial No. 147,779

20 Claims. (Cl. 114—151)

My invention relates broadly to navigation of ships, submarines and aircraft and more particularly to safety mechanism for improving the dirigibility of ships, submarines and aircraft.

5 This application is a division of my copending application, Serial Number 105,112, filed October 10, 1936, for "Safety mechanism for improving the dirigibility of ships, submarines and aircraft."

10 One of the objects of my invention is to provide an improved construction of navigation control mechanism by which steering of large vessels, submarine boats, and aircraft may be facilitated.

15 Another object of my invention is to provide an arrangement of navigation mechanism for vessels wherein means are associated with the rudder mechanism for variably displacing the fluid medium in which the vessel is navigated directly through the rudder for facilitating steering of the vessel under control of the rudder mechanism.

20 Still another object of my invention is to provide an arrangement of conduits through the rudder with means for displacing the fluid medium through the conduits for developing forces controllable for navigating the vessel.

25 A further object of my invention is to provide an arrangement of turbines constructed for directly acting upon the fluid medium for maneuvering a vessel in the fluid medium independently of the main propulsion system.

30 Other and further objects of my invention reside in the application of a turbine structure for propelling mechanism as applied to vessels, submarines and aircraft navigation as set forth more fully in the specification hereinafter following by reference to the accompanying drawing in which:

35 Figure 1 illustrates a hollow rudder equipped with reversible turbines operating in vertically and horizontally disposed conduits extending through the hollow rudder for controlling the displacement of fluid and the navigation of the vessels with which the rudder is associated and illustrating mechanical drive means for imparting rotation to the turbines through transmission from within the vessel; Fig. 2 shows a modified arrangement of rudder having electric drive means for the turbines which displace the fluid through the conduits; Fig. 3 is a horizontal sectional view taken on line 3—3 of Fig. 2; and Fig. 4 is a vertical sectional view taken on line 4—4 of Fig. 2.

40 Referring to the drawing in more detail, reference character 1 designates the hull of a vessel which may be of various types or constructions and in which there is arranged a stern bearing 2 for journaling the main propeller 3. The skeg or deadwood is indicated at 4. The rudder shoe 5 securing to the skeg or deadwood is indicated at

5 5. A stuffing box 6 is provided in the hull of the vessel through which the rudder post 7 extends. The rudder post 7 is pivoted or journaled at 8 in the rudder shoe 5. The rudder shown at 9 is of hollow construction, as will be pointed out hereinafter in more detail. A quadrant 10 is connected with the upper end of the rudder post 7 for operation from tiller cables leading to the wheel house.

10 The means employed in my invention herein described include fluid turbine devices arranged with inlet and outlet passages disposed in such directions as the maneuvering force may be desired. The turbine devices are preferably reversible so that the force may be effective in either 15 direction at the openings of the fluid passages in the hollow rudder.

15 The turbine which operates to force fluid through the vertically extending conduit is particularly useful in the operation of submarines 20 in assisting the submerging and emerging of the vessel.

25 As represented more clearly in Figs. 2—4, the hollow rudder 9 is provided with tubular conduits, or fluid passages 121, 122 which extend in a substantially vertical and horizontal direction and open at opposite portions of the rudder. A turbine is interposed in the path of each of the tubular conduits. Turbine 123 is located in conduit 121. Turbine 124 is located in conduit 122. 30 The turbines 123 and 124 are driven by electrical motors indicated at 123a and 124a or are driven through rotary shafts extending through hollow rudder post 7 from driving means interiorly of the vessel as indicated in Fig. 1. The motors 35 123a and 124a may be selectively started and stopped for driving the turbines in accordance with the required maneuvering of the vessel. The motors 123a and 124a are quickly reversible so that the displacement of the fluid through the 40 rudder structure may be instantly controlled.

45 On surface vessels vertical turbines may be omitted and only horizontal turbines employed.

With reference to the arrangement illustrated in Fig. 1 in which the turbines in the rudder are driven by transmission means extending from the interior of the vessel, the drives to the separate turbines are maintained wholly independent. The drive to the turbine 123 extends from shaft 26, extending through the hollow rudder post 7 50 and through a suitable bearing 27 to the miter gears 28 controlled by drive shaft 29. Turbine 124 is driven through shaft 30 extending through hollow rudder post 7 for mounting in bearing 31. Shaft 30 is driven through miter gears 32 from 55 shaft 33 extending into the interior of the vessel.

60 The hollow rudder 9 is provided with a face plate indicated generally at 34 which is removably connected in any suitable manner with the rudder casing to permit access to the interior of 60

the rudder and to the turbines contained therein as may be required.

Any suitable means may be provided for supporting the driving motors 123a and 124a interiorly of the hollow rudder.

Where the mechanism of my invention is applied to naval vessels subject to the destruction of war, I may employ armor plate as part of the construction of the hollow rudder for the protection of the turbines and the fluid conduits within the hollow rudder. The turbines are sufficiently isolated from the main body of fluid, due to relatively small size of opening and the length of the fluid conduit, so that the effects of percussion in the main body of fluid are minimized at the position of the turbines.

The turbines in the rudder may coact with turbines included in conduits in the hull of the vessel or with the main conveyor for facilitating the maneuverability of the vessel. That is to say, the turbines in the hollow rudder may integrate propulsion forces with respect to the main propeller 3 and aid in driving the vessel.

Wherever I use the expression "turbine" or "turbine pump" in the foregoing specification or in the appended claims, I intend to include any form of hydraulic pump; and by the term "impeller" I refer to the impelling element of such hydraulic pump without regard to any term or name associated with such impelling element by various manufacturers.

Wherever I refer to a "hollow rudder" it need be hollow only in such a sense as may be necessary for the inclusion and proper operation of the specified machinery.

While I have described my invention particularly in connection with surface vessels, I desire that it be understood that corresponding applications of my invention may be made for submarines and aircraft and no limitations upon my invention are intended other than may be imposed by the scope of the appended claims.

What I claim as new and desire to secure by Letters Patent of the United States is as follows:

1. Mechanism for maneuvering vessels comprising in combination a hollow rudder, means for angularly adjusting the rudder through selected vertical planes, tubular conduits extending horizontally from front to back of the rudder, and vertically from top to bottom, turbines each having an impeller, drive means for rotatively driving said impellers, means individual to each of said conduits for including one of said impellers in the fluid path thereof, and separate means for controlling the operation of said drive means for correspondingly controlling the discharge force of fluid through said rudder.

2. Mechanism for controlling the movement of vessels comprising a hollow rudder angularly adjustable in selected vertical planes and having a passage forming means extending horizontally from front to back thereof, and rotary motive means supported within said hollow rudder for variably controlling the movement of fluid through the passage in said rudder.

3. Mechanism for controlling the movement of vessels comprising a hollow rudder angularly adjustable in selected vertical planes and having a passage forming means extending vertically from top to bottom thereof, and rotary motive means supported within said hollow rudder for variably controlling the movement of fluid through the passage in said rudder.

4. Mechanism for maneuvering vessels comprising in combination a hollow rudder, means for angularly adjusting the rudder through se-

lected vertical planes, tubular conduits extending through the rudder, horizontally from front edge to back edge, and vertically from top edge to bottom edge, turbines each having an impeller, drive means for rotatably driving said impellers, means individual to each of said conduits for including one of said impellers in the fluid path thereof, and separate means for controlling the operation of said drive means for correspondingly controlling the discharge force of fluid through said rudder.

5. Mechanism for maneuvering vessels comprising in combination with a hollow rudder, a turbine pump disposed within said hollow rudder, said turbine pump having a duct running substantially horizontally and parallel with the horizontal axis of the rudder from front to back thereof, drive means for said turbine pump supported within said hollow rudder and effecting suction of the water at one end of duct, and discharge thereof at the opposite end whereby driving forces are developed by the movement of water through the duct, and means for controlling the operation of said drive means.

6. Mechanism for controlling the movement of vessels comprising a hollow rudder angularly adjustable in selected vertical planes, said rudder including independent conduits extending therethrough forming passages for water from front to back and from top to bottom of said rudder, and means disposed in each of said passages for variably controlling the flow of water through said passages.

7. Mechanism for controlling the movement of vessels comprising a hollow rudder angularly adjustable in selected vertical planes, said rudder including independent conduits extending therethrough forming passages for water from front to back and from top to bottom of said rudder, a turbine disposed in each of said conduits, said turbine including a casing formed integral with the conduits, an impeller rotatably mounted in each casing, and separate means for imparting rotary movement to each of said impellers for controlling the flow of water through said conduits.

8. Mechanism for controlling the movement of vessels comprising a hollow rudder angularly adjustable in selected vertical planes, said rudder including independent conduits extending therethrough forming passages for water from front to back and from top to bottom of said rudder, a turbine individual to each of said conduits, each turbine including a casing connected with its associated conduit, an impeller disposed in said casing, means in said hollow rudder for independently driving said impellers, and means external to said hollow rudder for controlling the operation of the aforementioned means.

9. Mechanism for maneuvering vessels comprising in combination a hollow rudder, means for angularly adjusting the rudder through selected vertical planes, a tubular conduit extending horizontally from front to back of said rudder, a turbine having an impeller means for mounting said turbine within said rudder, drive means disposed within said hollow rudder for rotatively driving said impeller, means for including said impeller in the fluid path of said conduit, and separate means for controlling the operation of said drive means for correspondingly controlling the discharge force of fluid through said rudder.

10. Mechanism for maneuvering vessels comprising in combination a hollow rudder, means for angularly adjusting the rudder through se-

lected vertical planes, a tubular conduit extending through the rudder horizontally from front edge to back edge, a turbine comprising an impeller and a casing, said casing being connected with said tubular conduit, drive means extending through said casing and connected with said impeller for rotatively driving said impeller, said casing including said impeller in the fluid path of said conduit, and separate means for controlling the operation of said drive means for correspondingly controlling the discharge force of fluid through said rudder.

11. Mechanism for controlling the movement of vessels comprising a hollow rudder of metallic sheet material forming spaced substantially parallel walls, said rudder being angularly adjustable in selected vertical planes and including an independent conduit extending therethrough between said substantially parallel walls forming a passage for water from front to back of said rudder, and means disposed in said passage for variably controlling the flow of water through said passage.

12. Mechanism for controlling the movement of vessels comprising a hollow rudder angularly adjustable in selected vertical planes, said rudder including an independent conduit extending therethrough forming a passage for water from front to back of said rudder, a turbine supported within said hollow rudder and disposed in said conduit, said turbine including a casing formed integral with the conduit, an impeller rotatively mounted in said casing, and separate means disposed within said hollow rudder for imparting rotary movement to said impeller for controlling the flow of water through said conduit.

13. Mechanism for controlling the movement of vessels comprising a hollow rudder angularly adjustable in selected vertical planes, said rudder including an independent conduit extending therethrough forming a passage for water from front to back of said rudder, a turbine supported within said hollow rudder and including a casing connected with said conduit, an impeller disposed in said casing, motive means enclosed by said hollow rudder for independently driving said impeller, and means external to said hollow rudder for controlling the operation of the aforementioned means.

14. Mechanism for maneuvering vessels comprising in combination a hollow rudder, means for angularly adjusting the rudder through selected vertical planes, a tubular conduit extending vertically from top to bottom of said rudder, a turbine having an impeller, motive means for rotatively driving said impeller located within said rudder, means for including said impeller in the fluid path of said conduit, and separate means for controlling the operation of said drive means for correspondingly controlling the discharge force of fluid through said rudder.

15. Mechanism for maneuvering vessels comprising in combination a hollow rudder, means for angularly adjusting the rudder through selected vertical planes, tubular conduits extending horizontally from front to back and from top to bottom of the rudder, turbines each having an impeller, drive means supported within said hollow rudder and external to said conduits for rotatively driving said impellers, means individual to each of said conduits for including one of said impellers in the fluid path thereof, and separate

means for controlling the operation of said drive means for correspondingly controlling the discharge force of fluid through said rudder.

16. Mechanism for maneuvering vessels comprising in combination a hollow rudder, means for angularly adjusting the rudder through selected vertical planes, tubular conduits extending vertically from top to bottom and horizontally from front to back of the rudder, turbines each having an impeller, means supporting said turbines within said hollow rudder, drive means disposed within said hollow rudder for rotatively driving said impellers, a casing individual to each of said conduits for including one of said impellers in the fluid path thereof, and separate means for controlling the operation of said drive means for correspondingly controlling the discharge force of fluid through said rudder.

17. Mechanism for maneuvering vessels comprising in combination a hollow rudder, means for angularly adjusting the rudder through selected vertical planes, tubular conduits extending substantially normal to each other in different vertical planes through said rudder, turbines supported within said rudder and each having an impeller, drive means located within said rudder for rotatively driving said impellers, means individual to each of said conduits for including one of said impellers in the fluid path thereof, and separate means for controlling the operation of said drive means for correspondingly controlling the discharge force of fluid through said rudder.

18. Mechanism for maneuvering vessels comprising in combination a hollow rudder, means for angularly adjusting the rudder through selected vertical planes, tubular conduits disposed at an angle to each other and off-set in vertical planes with respect to each other and extending from edge to edge of said hollow rudder, hydraulic pumping devices located in each of said tubular conduits, motive means for driving said hydraulic pumping devices for variably controlling the displacement of water through the tubular conduits extending through said hollow rudder.

19. Mechanism for maneuvering vessels comprising in combination a hollow rudder, means for angularly adjusting the rudder through selected vertical planes, a tubular conduit extending through said hollow rudder from edge to edge thereof in substantially a vertical direction with the axis thereof off-set from a plane passing through the central axis of the rudder, a hydraulic pumping device disposed within said hollow rudder, said hydraulic pumping device having an impelling element located in the path of said conduit for variably controlling the displacement of water through the conduit.

20. Mechanism for maneuvering vessels comprising in combination a hollow rudder, means for angularly adjusting the rudder through selected vertical planes, a tubular conduit extending through said hollow rudder from edge to edge thereof in substantially a horizontal direction with the axis thereof off-set from a plane passing through the central axis of the rudder, a hydraulic pumping device disposed within said hollow rudder, said pumping device having an impelling element located in the path of said conduit for variably controlling the displacement of water through the conduit.
